UNITED STATES PATENT OFFICE

2,542,078

DETACHABLE HEEL

Thomas Gilmour, Brooklyn, N. Y.

Substituted for abandoned application Serial No.
572,196, January 10, 1945. This application
June 15, 1948, Serial No. 33,085

4 Claims. (Cl. 36—36)

1

This invention relates to interchangeable heels and is a substitute for my abandoned application Serial No. 572,196 filed January 10, 1945.

More particularly, the invention proposes the construction of a heel and means for releasably attaching the same to the heel base of a shoe in a manner so that the heel may be quickly and easily detached and replaced with a new heel, when desired, without the use of any tools or skill on the part of the person making the change.

Still further, the invention proposes the combination with a heel base having a groove formed in and extending along two sides and the back of a channel-like horseshoe member engaged about said base and having its top arm engaging in and along said groove, and a heel having a groove formed in and extending along its sides and back and engaged by the bottom arm of said channel-like horseshoe member by which said heel is supported in position.

The invention contemplates the use of a plate mounted on the front of said heel base and having openings through which the ends of said horseshoe member pass by which the heel may be locked in position.

Still further the invention proposes the provision of latches on said plate releasably engaging the ends of said horseshoe member.

Another object of the invention resides in constructing said channel-like horseshoe member of more than one part, preferably hingedly connected together.

Another object of the invention is the construction of a device as mentioned which is simple and durable and which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a fragmentary perspective view of a shoe provided with an interchangeable heel constructed in accordance with this invention.

Fig. 2 is a fragmentary vertical sectional view taken on the line 2—2 of Fig. 1.

Fig. 3 is a back elevational view of the shoe 50 shown in Fig. 1.

Fig. 4 is a fragmentary vertical sectional view taken on the line 4—4 of Fig. 1.

Fig. 5 is a bottom plan view of the heel, per se. The interchangeable heel, in accordance with 55

the present invention, is used in combination with a heel base 15 of a shoe 16. This heel base 15 is formed with a groove 17 which extends along its sides and back. A horseshoe member 18 which 5 is channel-shaped in cross-section, engages about said heel base 15 and has its top arm engaging in and along said groove 17. A heel 19 is positioned upon the bottom of the heel base 15. This heel 19 has a groove 20 which is engaged by 10 the bottom arm of the horseshoe member 18 and by which the heel 19 is supported.

A plate 21 is mounted on the front of the heel base 15, preferably with several screws 22. This plate 21 has openings 23 through which end lugs 15 24 from the ends of said horseshoe member 18 pass. Latches 25 are mounted on the plate 21 and releasably engage the lugs 24 for locking the channel-like horseshoe member 18 in position.

20 The latches 25 are in the nature of pivotally mounted hooks. Pintles 26 are used to pivotally mount the latches 25. The front ends of the latches are provided with hook portions which engage through small openings 27 formed in the 25 lugs 24.

The channel-like horseshoe member 18 is formed from two sections. There is a right hand section and a left hand section which are hingedly connected at the back of the heel by a hinge 28. The heel 19 may be of rubber, or any other 30 suitable material.

When the heel 19 becomes worn it may be replaced. To do this the latches 25 are first opened. Then the channel-like horseshoe member 18 is 35 slipped slightly rearwards so that the lugs 24 disengage from the openings 23 in the plate 21. Then the side sections of the channel-like horseshoe member 18 are spread open about the hinge 28. This frees the heel 19 which may then be 40 removed and replaced.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. Means for securing in position a channel-shaped horseshoe member engaged with parallel grooves formed about the side and back of a heel and the heel base of a shoe, comprising a plate 55 secured to the front face of the heel, forwardly

extended lugs on the ends of the horseshoe member, said plate being formed with openings aligned with and through which said lugs project, and latches on said plate and engaging said lugs.

2. Means for securing in position a channel-shaped horseshoe member engaged with parallel grooves formed about the side and back of a heel and the heel base of a shoe, comprising a plate secured to the front face of the heel, forwardly extended lugs on the ends of the horseshoe member, said plate being formed with openings aligned with and through which said lugs project, and latches on said plate and engaging said lugs, said lugs having their free ends projected beyond the front face of said plate and formed with small openings, said latches comprising hooks pivotally mounted on the front face of said plate and engaged with the small openings of said lugs.

3. In a shoe having a heel base formed with a groove about the sides and back thereof and a separate heel beneath the heel base formed with a groove about the sides and back thereof and extended parallel to the groove of the heel base, means releasably securing the heel to the heel base, comprising a channel-shaped horseshoe member formed of superimposed sections engaged about the heel and heel base with the upper section engaging the groove of the heel base and the lower section engaging the groove of the heel, a hinge pivotally connecting said sections together, a plate secured to the front face of the heel base and having its bottom portion extended downward over the front face of the heel, said plate being formed with openings aligned with the ends of said sections, forwardly extended lugs formed on the ends of said sections and projected into said openings for holding said sections against pivoting relative to one another, and means releasably securing said horseshoe member to said plate.

4. In a shoe having a heel base formed with a groove about the sides and back thereof and a separate heel beneath the heel base formed with

a groove about the sides and back thereof and extended parallel to the groove of the heel base, means releasably securing the heel to the heel base, comprising a channel-shaped horseshoe member formed of superimposed sections engaged about the heel and heel base with the upper section engaging the groove of the heel base and the lower section engaging the groove of the heel, a hinge pivotally connecting said sections together,

5 10 15 20 25

a plate secured to the front face of the heel base and having its bottom portion extended downward over the front face of the heel, said plate being formed with openings aligned with the ends of said sections, forwardly extended lugs formed on the ends of said sections and projected into said openings for holding said sections against pivoting relative to one another, and means releasably securing said horseshoe member to said plate, the lugs of one of said sections being of a length to extend completely through their respective openings and formed beyond the front face of said plate with holes, said latter-mentioned releasable securing means comprising hooks pivotally mounted on the front face of said plate and engaged into said holes.
